UNITED STATES PATENT OFFICE.

NICCLAS EMILIEEN METHLIN, OF PARIS, FRANCE, ASSIGNOR TO SCHNEIDER & CIE, OF PARIS, FRANCE, A LIMITED JOINT STOCK COMPANY OF FRANCE.

PERCUSSION FUSE.

Application filed April 4, 1925. Serial No. 20,820.

To all whom it may concern:

Be it known that I, NICCLAS EMILIEEN METHLIN, a citizen of the Republic of France, resident of Paris, France, have invented new and useful Improvements in or Relating to Percussion Fuses, which is fully set forth in the following specification.

This invention relates to improvements in the known forms of percussion fuses comprising a detonator-holder and a striker body one of which is enclosed by or enters into the other for their mutual guidance, each of these parts of the firing mechanism being provided with a head the external 15 surface of which is frusto-conical in shape or is in the form of a spherical cap, by means of which heads the said parts bear against the internal surface of a chamber or cup of corresponding shape constituted 20 by the fuse body.

The known fuse of this type, constructed according to the invention, and which comprises, also according to a known principle, safety members which are withdrawn from 25 operation by the action of the centrifugal force but do not escape outside the fuse body, is characterized by the provision of simple and efficient devices which prevent the said safety members, after their removal 30 from returning towards the axis of the fuse body and thus make it impossible for the mechanism to operate when an obstacle is struck.

For this purpose, the safety devices which 35 are removed, due to the centrifugal force, are combined with a member which can move longitudinally in the direction of its axis and which is acted upon by a spring which constantly tends to drive it back, the 40 said members being thus interposed between the striker body and the said safety members as soon as the latter have been removed by the action of the centrifugal force.

Figures 1 and 2 in the accompanying drawing, illustrate in sectional elevation, one form of construction of the invention in two different working positions.

Figs. 3, 4 and 5, are longitudinal sectional elevations illustrating another embodiment 50 of the invention in three different working positions.

In the embodiment of the invention illustrated in Figs. 1 and 2, A is a fuse body 55 comprising two opposite frusto-conical

cups or bearing surfaces A¹, A² in which rest the striker body B and the detonator holder C, one of which is enclosed by and enters into the other to provide a mutual guidance. D is the spring which normally separates the striker body B from the detonator holder C.

The segments E, which are held pressed against the pin of the striker body by a spring e coiled round them constitute a 60 safety device. A ring F guided in an annular recess provided in the body B, bears upon the upper surface of these segments, and a spring f pressing against the said ring and the bottom of the said body B, 65 constantly tends to force the ring back.

When the projectile rotates, the segments, under the action of the centrifugal force, are forced outwards and press against the wall b of an enlarged chamber provided in 70 the body B, which allows the ring F to be forced back by the spring f and to thus occupy the position shown in Figure 2. The segments E cannot after this return to 75 towards the axis of the fuse body, or more exactly towards the axis of the mechanism B—C.

When the projectile strikes an obstacle and whatever be the inclination of the projectile relatively to the latter the striker makes contact with the detonator, the springs D and f being compressed.

In the embodiment of the invention illustrated in Figs. 3, 4 and 5, the striker proper B¹, instead of being an integral part of the body B, can move longitudinally in the latter. The safety members consist of balls E normally secured around the striker in conical hollows b¹, by means of a spring g which constantly tends to force the striker B¹ back and to bring it into position for arming the fuse when it makes contact, by means of the shoulders b², with the partition wall b³ of the body B.

When at rest, the balls H are secured between the pin of the striker and the guiding wall b³ of the body B.

When the projectile rotates, the balls E are forced outwards, by the action of the centrifugal force, and this causes them to leave the hollows b¹, the striker B¹ being raised and the spring g being compressed as shown in Figure 4. These balls E finally press against the walls b⁴, and this enables the spring g to expand and force down the

striker B^1 which is thus brought into the armed position shown in Figure 5. At the same time the balls H are forced against the wall b^5 and are thus wedged between the 5 striker and a shoulder b^6 on the body B , thus holding the striker stationary in the armed position.

The travel α which the detonator holder C can have is naturally greater than the 10 distance y^1 which separates the detonator from the point of the striker in the armed position (Fig. 5), while it is less than the distance y which separates the detonator from the point of the striker when the projectile is at rest (Fig. 3).

As it is seen, in this case it is the striker B^1 , which is movable relatively to the body B in which it is guided, which takes the place of the ring F in the preceding example, and, as in the first example any movement of the safety members E back towards the axis of the mechanism $B-C$ is rendered impossible as soon as these members have been removed and rendered ineffective. 25

Having now particularly described and ascertained the nature of my said invention and in what manner the same is to be performed, I declare that what I claim is:

30 1. A device for a projectile comprising a body portion having a chamber therein, a pair of elements mounted in telescopic relation within said chamber, a longitudinally movable member having sliding engagement 35 with one of said elements, means normally tending to move said member in one direction, and safety members normally preventing movement of said member adapted to move radially by centrifugal force, the return of the safety members to normal position being prevented by said longitudinally movable member.

2. A fuse for a projectile comprising a body portion having a chamber therein, a 45 pair of elements mounted in telescopic relation within said chamber, one of said elements constituting a detonator holder, a longitudinally movable member extending within one of said elements, resilient means for moving said member in one direction, and radially movable safety members normally preventing movement of said longitudinally movable member, the latter being adapted to positively lock said safety members in 50 armed position.

3. A fuse for projectiles comprising a body portion having a chamber therein, a pair of elements mounted in telescopic relation within said chamber, one of said elements constituting a detonator holder, a 60 longitudinally movable member having sliding engagement with one of said elements, resilient means adapted to move said longitudinally movable member in one direction,

centrifugal safety members for normally 65 preventing movement of said member, and resilient means interposed between said detonator holder and the other of said elements.

4. A fuse for projectiles comprising a fuse 70 body, a pair of elements movably mounted in telescopic relation within the body portion, a longitudinally movable sleeve having sliding engagement with one of said elements, resilient means interposed between 75 said sleeve and one of said elements, safety members normally preventing movement of said sleeve, said safety members being adapted to be moved radially by centrifugal force, and means for yieldingly resisting radial movement of said safety members, the return of said safety members to normal position being prevented by said sleeve.

5. A fuse for projectiles comprising a 80 body portion having a chamber therein, a detonator holder and a striker body movably mounted in telescopic relation within 85 said chamber, a longitudinally movable member having sliding engagement with said striker body, resilient means adapted 90 to move said member longitudinally, centrifugally actuated safety members normally preventing longitudinal movement of said member and adapted to move radially to arm the fuse, the return of the safety members to normal position being prevented by said longitudinally movable member.

6. A fuse for projectiles comprising a body portion having a chamber therein, a striker body and a detonator holder movably mounted in telescopic relation within 100 said chamber, a striker carried by said striker body, a sleeve surrounding said striker, resilient means interposed between the sleeve and the striker body, centrifugally 105 actuated safety members interposed between the detonator holder and the sleeve, resilient means normally preventing radial movement of said safety members, and resilient means interposed between the detonator holder and the striker.

7. A fuse for projectiles comprising a body portion having a chamber therein, a striker body and a detonator holder movably mounted in telescopic relation within 110 said chamber, a striker secured to the striker body, a movable sleeve surrounding the 115 striker, resilient means interposed between the sleeve and the striker body, and centrifugally actuated safety members normally preventing movement of said sleeve and adapted to be moved radially by centrifugal force to arm the fuse, said sleeve being adapted to lock said safety members in 120 armed position.

In testimony whereof I have signed this specification.

NICOLAS EMILIEU METHLIN.
